UNITED STATES PATENT OFFICE.

JOHN FOULTZ, OF REA, MISSOURI.

TATTOOING INSTRUMENT.

SPECIFICATION forming part of Letters Patent No. 699,915, dated May 13, 1902.

Application filed August 23, 1901. Serial No. 73,001. (No model.)

To all whom it may concern:

Be it known that I, JOHN FOULTZ, a citizen of the United States, residing at Rea, in the county of Andrew and State of Missouri, have 5 invented certain new and useful Improvements in Tattooing Instruments; and I do hereby declare the following to be a full, clear, and exact description of the invention, such as will enable others skilled in the art to which 10 it appertains to make and use the same.

My invention relates to improvements in that class of tattooing instruments which are designed for the marking of live stock, such as bovines and other animals; and the objects of my improvements are, first, to provide an instrument by the use of which any desired character or characters—such as record-number, index-number, individual number or mark, &c.—may be pricked into the 15 nose of an animal with ease and facility; second, to so arrange the parts of a tattooing instrument that it may be used in marking variously sized and proportioned noses of animals; third, to so construct a tattooing instrument that it will be cheap in cost of manufacture and very durable. I attain these 20 objects by the mechanism illustrated in the accompanying drawings, in which—

Figure 1 is a perspective view of a part of 25 my invention, certain other parts seen in Fig. 2 being removed to avoid obscurity. Fig. 2 is a perspective view of parts removed from Fig. 1. Fig. 3 is a bottom plan of characters. Fig. 4 is a transverse section cut vertically 30 through a perspective view of characters or character-holder and their operating limb or lever. Fig. 5 is a side elevation of my invention as it appears when in use.

My invention comprises two essential features, viz: first, two-limbed tongs suitably arranged for holding an animal by the nose, and, second, a third limb pivotally attached to said tongs and suitably arranged to drive tattooing-needles into the nose of said animal 45 while being thus held, as hereinafter more fully described.

In the construction of my invention the two suitably-shaped jaws 1 (see Fig. 1) are preferably telescoped upon limbs 2 and secured thereon by set-screws 3, as seen in Fig. 1, or said jaws 1 may be formed integral with limbs 2. Limbs 2 are pivotally attached to

gether by stud 4, perforated at 5 for the reception of bolt 6, (see Fig. 2,) arranged to pass through perforation 7 in limb 8 and perforation 5 in stud 4 for the pivotal attachment of limb 8 to stud 4, in which stud 4 passes upward through mortise 9 (see Fig. 2) in limb 8. Limb 8 carries character-holder 10, which carries characters 11, secured therein by their suitable mortise telescoping upon plate 12. (See Fig. 4.) Characters 11 have their face or under side suitably studded with prick-points or tattooing-needles 11^a, as seen in Figs. 3 and 4. The two limbs 2 are provided with suitable handles 13 and the limb 8 with handle 14.

In the operation of my invention the operator grasps handles 13 and holds them horizontally, separating jaws 1 in the same manner 70 as an ordinary pair of tongs. In the meantime handle 14 will gravitate pivotally on bolt 6, carrying upward the character-holder 10 and the characters 11 held therein. The operator then inserts one each of the two jaws 75 1 in each nostril 15 of animal 16, and on pressing handles 13 toward each other jaws 1 will close upon and press against both sides of septum 17 of the nose 18 of animal 16, thus 80 securely restraining or holding animal 16, after which handles 13, being close together, may be grasped by one hand of the operator, leaving the other hand free, which grasps handle 14, which upon being drawn upward pivotally on bolt 6 causes limb 8 to descend, carrying tattooing-needles 11^a into the nose 18 of animal 16, pricking perforations into nose 85 18. By movements in reverse to the ones described the instrument is removed from nose 18 of animal 16, after which any tattooing-90 ink (not shown) of suitable color is rubbed into the perforations in nose 18 of animal 16 in the usual tattooing manner.

It is preferred that the described tattooing should be done on nose 18 in a straight line 95 across said nose close to and just above nostrils 15, as indicated at 18.

Jaws 1 are formed of such peculiar shape (see Fig. 1) as will fit in nostril 15 and also while holding animal 16 by septum 17 be of 100 suitable form to afford a backing or support for nose at 18, thus preventing any yielding of nose at 18 while being pressed by needles 11^a. The detachable jaws 1 may be replaced by any

variously-formed jaws suitably shaped for various animals.

I am aware that tattooing characters 11, provided with suitably-arranged tattooing-needles 11^a, have been used for tattooing animals in the ear, and therefore do not claim the tattooing of an animal in the broadest sense; but I am not aware that tattooing of animals upon their noses has been done here-
10 tofore or that any instrument other than my invention has been devised for such work. Therefore

What I claim as new and original, and desire to secure by Letters Patent, is—

15 1. In a tattooing instrument, the combination with two-limbed tongs having suitable jaws and handles; of a third limb, pivotally

attached to said tongs and carrying a holder and tattooing devices carried by said holder as shown, and specified.

20

2. In a tattooing instrument the combination with two-limbed tongs provided with handles, and having jaws of suitable shape to fit in the nostrils and hold and support the nose of an animal, of a third limb, pivotally attached to said two-limb tongs, and provided with means for tattooing the nose, as specified.

25

In testimony whereof I affix my signature in presence of two witnesses.

JOHN FOULTZ.
